UNITED STATES PATENT OFFICE

RAYMOND G. F. LOEWY, OF NEW YORK, N. Y.

DESIGN FOR A LOCOMOTIVE

Application filed April 23, 1932. Serial No. 43,590. Term of patent 7 years.

To all whom it may concern:

Be it known that I, RAYMOND G. F. LOEWY, a citizen of the Republic of France, residing in the borough of Manhattan, city, county, and State of New York, have invented a new, original, and ornamental Design for a Locomotive, of which the following is a specification, reference being had to the accompanying drawings, forming part thereof.

Figure 1 is a side elevation of a locomotive showing my new design, both sides of which

present substantially the same appearance, and

Figure 2 is a front elevation of the same on an enlarged scale.

I claim:

The ornamental design for a locomotive as shown and described.

In testimony whereof I have affixed my signature to this specification.

RAYMOND G. F. LOEWY.
